CLAIM

The ornamental design for a container for a blender, as shown and described.

DESCRIPTION

FIG. 1 is a top, left side perspective view of a container for a blender showing our new design;

FIG. 2 is a bottom, right side perspective view thereof;

FIG. 3 is a top plan view thereof;

FIG. 4 is a bottom plan view thereof;

FIG. 5 is a rear elevational view thereof;

FIG. 6 is a front elevational view thereof; and,

FIG. 7 is a left side elevational view thereof, the right side being a mirror image of FIG. 7.

1 Claim, 4 Drawing Sheets
